EXTENSION LEAF TABLE

John C. L. Viehmann, Manhasset, N. Y.

Application July 12, 1946, Serial No. 683,213

9 Claims. (Cl. 311—55)

1

My invention relates to an extension leaf table, and a means of constructing the same so as to achieve additional support for the extension leaves when they are in extended supporting position.

Extension leaf tables of the type here involved, that is to say, tables in which the extension leaves are mounted on the table so as to be housed beneath the fixed table top and extendable to a supporting position in abutting alignment with the tabletop, are well-known articles of manufacture and have proved exceedingly popular commercially. One of the prime difficulties in constructing tables of this type has been the provision of suitable supporting means for the extension leaf when it is in its extended supporting position so that it will retain its alignment with the table top despite the application of weight thereto, either in the form of articles supported thereby or the weight of people leaning thereon. Various methods have in the past been proposed to attain such support, but all of them are characterized by requiring relatively complicated structures which are both difficult to manufacture and extremely susceptible to damage.

It is a prime object of the present invention to provide a table construction in which positive and adequate support is provided for the extension leaf when it is in its extended supporting position, which support is achieved by means of a simple structure which is at once both easy to manufacture and assemble and extremely sturdy.

It is a further object of the present invention to provide such a table in which the supporting means for the extension leaf simultaneously serves as its guiding means as the leaf is moved from its housed to its extended supporting position.

It is still another object of the present invention to provide a table construction in which the supporting and guiding means is so constructed and so coacts with the remainder of the table assembly that movement of the extension leaf from its housed to its extended supporting position is simply and positively achieved and controlled.

To the accomplishment of the foregoing objects and such other objects as may hereinafter appear, the present invention relates to an extension leaf table as sought to be defined in the appended claims and as described in this specification taken together with the accompanying drawings, in which:

Fig. 1 is a perspective view of a table having one extension leaf in its extended supporting position

2

and having the other extension leaf in its housed position;

Fig. 2 is a fragmentary end view of an end rail of the table showing the position of the extension leaf guiding and supporting means when the extension leaf is in its extended supporting position;

Fig. 3 is a similar view showing the guiding and supporting means in a different position;

Fig. 4 is a perspective view of another embodiment of the end rail;

Fig. 5 is a view similar to Fig. 4 except that the aperture in the end rail is provided at its lower surface with an anti-friction bearing;

Fig. 6 is a view of the table of Fig. 1 taken from underneath looking up; and

Fig. 7 is a view taken along the line 7—7 of Fig. 6.

The table of my invention includes a fixed table top, generally designated A, beneath which is housed at least one extension leaf, generally designated B, which is movable from its housed position below the fixed tabletop A (right-hand leaf B of Fig. 1) to an extended supporting position in abutting alignment with the fixed table top A (left-hand extension leaf B of Figs. 1 and 7), in which latter position its upper surface constitutes a substantially coplanar extension of the fixed tabletop A. The extension leaf B is guided in its motion between these two positions by at least one guiding and supporting means, here shown in the form of a slide bar, generally designated C, which is so shaped as to be slidable through an aperture D in an end rail E of the table.

The aperture D is formed with an upper constricted neck portion F which opens to the top of the end rail E and a portion G of the slide bar C is so shaped as to be passable through the constricted neck portion F of the aperture D. This constricted portion G is so positioned on the slide bar C as to come into registration with the aperture D when the extension leaf is not in its extended supporting position, and preferably when the extension leaf B has been extended beyond its supporting position. That portion of the slide bar C which comes into registration with the orifice D when the extension leaf B is in its extended supporting position is of such a size as not to be passable through the constricted neck portion F of the aperture D. Consequently, once the extension leaf B has been raised above its housed position—which is accomplished by aligning the constricted body portion G of the slide bar C with the aperture D and in then raising the same cut of the aperture

D via its constricted neck portion F—and is then brought into its supporting position in abutting alignment with the table top, the slide bar C will rest upon the upper edge of the end rail E at the constricted neck portion F of the aperture D. Since the slide bar C will not then be passable through the constricted neck portion F, it will be supported in its position by the end rail E, and since it is fixed to the extension leaf B the latter too will be supported in its extended supporting position. It is to be noted that the point of support thus afforded is very closely positioned with respect to the extension leaf B, this being desirable for obvious mechanical reasons.

Having thus delineated the essential features of my construction, I shall now describe in detail the embodiment of my invention here illustrated. The table comprises a fixed table top A supported by means of a framework 2 somewhat above the side rails 4 and 6 and the end rails E of the table body. Legs 8 are secured thereto as by the use of angle irons 10 so that the whole may be supported in raised position as is customary. Two extension leaves may be housed between the fixed table top A and the side and end rails 4, 6 and E as shown. To each of these extension leaves B are attached, by means of screws 12, a pair of slide bars C which terminate at their outer ends 14 preferably somewhat inboard of the outer edge 16 of the extension leaf B so that they will not interfere with access thereto.

The slide bars as here illustrated take the form of metal tubes, preferably hollow in order to save weight, the use of this form of slide bar being extremely desirable because of the inexpensive nature of such elements.

Each of the end rails E is provided with a pair of apertures D which are, to conform to the slide bars C here illustrated, of generally circular cross-section and are each provided with a constricted neck portion F open to the top of the end rail E. The cross-sectional size of the slide bars C and apertures D are so related that the slide bars are freely slideable within the apertures D but are not passable through the constricted neck portion F thereof. A portion G of each slide bar C is, however, constricted to an extent less than the width of the constricted neck portion F so that when said portion G is brought into registration with the orifice D, the slide bar may be lifted out of the orifice D via the constricted neck portion F. Formation of the constricted body portion G of the slide bar C is extremely simplified when the slide bar C is, as here shown, in the form of a hollow metal tube since mere application of a constricting tool of sufficient strength will suffice for the proper shaping of the bar.

In order to further assist in the guiding of the slide bars C, the inner ends 17 thereof pass through and are slideable within apertures 18 formed in brackets 20 attached to the central framework 2. These brackets 20 are so positioned, and the slide bars C are of such a length, that at no time during the normal manipulation of the extension leaves B to which the slide bars C are attached will the ends 16 of the bars C be withdrawn from the orifices 18. In order to ensure that this takes place, the inner ends 16 of the bars C are provided with stop elements 22, here shown in the form of a screw (Fig. 7) which projects from the surface of the bar C an amount sufficient to prevent withdrawal of the bar C

from the orifice 18. As an additional control feature, it may be desired to so position the stop member 22 on the bar C that when it comes into contact with the bracket 20, thus limiting further extension of the slide bar C, the constricted body portion G of the slide bar C will be within the orifice D and the extension leaf B will be in a position of extension beyond that which it assumes when it is in its supporting position in abutting alignment with the fixed table top A.

With the construction just described, an extension leaf B, when in its housed position, may be grasped and extended, the slide bars C attached thereto thus sliding through the apertures D and 18 until the stop member 22 abuts against the brackets 20 and positively limits further extension of the leaf B. At such time, the constricted body portion G of the slide bar C is in the aperture D, and consequently if the extension leaf B be raised, upward motion thereof will be permitted, the slide bar C moving up and out of the aperture D which formerly confined it by reason of its constricted body portion G moving through the aperture's constricted neck portion F. The extension leaf B may thus be raised to a position in alignment with the fixed table top A and may then be moved inwardly to abut the same, upon which inner movement an unconstricted portion of the slide bar C will be brought into registration with the upper edge of the end rail E over the constricted neck portion F. Since this portion of the slide bar C will not pass through the constricted neck portion F, the slide bar will be supported atop the end rail E and consequently the extension leaf B will similarly be supported. It will be apparent that by the proper choice of dimensions of the various elements the extension leaf B can thus be supported in a position in close alignment with the fixed table top A, as is best shown in Fig. 7.

In order to increase the support afforded the extension leaf B and in order to facilitate alignment thereof with the fixed table top A, the abutting edges 24 and 26 of the fixed table top A and the extension leaf B, respectively, may be so shaped as to interlock, preferably with the edge 24 substantially supporting the edge 26, as is best shown in Fig. 7.

In order to ensure a continuing alignment between the fixed table top A and the extension leaf B when it is in its extended supporting position, a spring 28 may be employed, one end 30 of which may be fastened in any suitable manner to the framework 2 and the other end 32 of which may be secured to the underside of the extension leaf B. As the leaf B is moved to its extended position, the spring 28 is resiliently expanded, and when the leaf B is in its extended supporting position in abutting alignment with the fixed table top A, the spring 28 is constantly exerting tension thereon tending to pull it toward the fixed table top A. By this means not only is the extension leaf B maintained in abutting relation with the fixed table top A, but the positive cooperation of the end surfaces 26 and 24 is ensured.

The aperture D may take any form which permits the accomplishment of the structural relationships above described. It is preferred that this form be generally circular, thus corresponding to the preferred form of the slide bar C, but that the upper part of the circle be eliminated by extending the upper edge of the end rail E so that the aperture D presents in cross-section a shape corresponding to a portion of a circle greater than a semi-circle but less than a full circle,

in which event the missing portion of the circle defines its constricted neck portion F. In so forming the aperture D, only a single boring or drilling operation is necessary to shape both the aperture D and the constricted neck portion F. Such an aperture D is illustrated in Figs. 1, 2, 3 and 6.

For heavy duty, however, it may be found that the constricted neck portion F thus formed is in substantial and the thin walls thereformed, particularly at its inner edges, may tend to become distorted, thus lessening the support afforded the extension leaf B. In such cases, the aperture D may be formed as illustrated in Figs. 4 and 5, where it assumes a keyhole shape in cross-section. More than one operation is necessary to form an aperture D of this shape and for that reason the previously described aperture shape is preferred where sufficient support will be afforded thereby.

During the motion of the extension leaf B from its housed position to the position where the constricted body portion G of the slide bar C comes within the aperture D, the slide bar C may carry the weight of the extension leaf B and may rest upon and slide over the bottom surface of the aperture D. In order to facilitate this sliding, the aperture illustrated in Fig. 5 is provided on its lower surface with a metal plate 34 within which is retained a plurality of ball bearings 36, thus defining an anti-friction bearing over which the slide bar C may slide, in this manner greatly facilitating the ease of manipulation of the extension leaf B.

By the construction as above described, I have formed an extension leaf table, the various elements of which may be manufactured and shaped in an exceedingly simple manner, these elements when assembled constituting a table of pleasing appearance which affords a maximum of support to the extension leaves B thereof when those leaves are in their extended supporting position. This support is provided at a point as close to the extension leaves B as it is possible to come and at the same time not have unsightly and dangerous projections from the table when the extension leaf B is in its housed position.

It will be apparent that many variations may be made in the details of construction of this table without departing from the spirit of the invention as defined in the following claims:

I claim:

1. In an extension leaf table having a table body including an end rail, a table top, and supporting legs therefor, an extension leaf mounted on said table body so as to be movable to an extended supporting position in abutting alignment with the table top and to a contracted position under the table top, and a support for the extension leaf comprising a slide bar carrying said leaf and slidible in an aperture in said end rail, said aperture having a constricted neck portion open at the top of said rail and said slide bar having a constricted body portion extending from top to bottom thereof and completely passable through said constricted neck portion when the leaf is moved to an extended position in which said constricted body portion is in alignment with said neck portion, an unconstricted part of said slide bar larger than said neck portion resting on and being supported by the top of said rail on said constricted neck when the leaf is in abutting alignment with the table top.

2. In an extension leaf table having a table body including an end rail, a table top, and supporting legs therefor, an extension leaf mounted

on said table body so as to be movable to an extended supporting position in abutting alignment with the table top and to a contracted position under the table top, and a support for the extension leaf comprising a slide bar carrying said leaf and slidible in an aperture in said end rail, said aperture having a constricted neck portion open at the top of said rail, and said slide bar having a constricted body portion extending from top to bottom thereof and completely passable through said constricted neck portion only when the leaf is moved to a position extended beyond its supporting position in which said constricted body portion is in alignment with said neck portion, an unconstricted part of said slide bar larger than said neck portion resting on and being supported by the top of said rail on said constricted neck when the leaf is in its supporting position in abutting alignment with the table top.

20 3. In an extension leaf table having a table body including an end rail, a table top, and supporting legs therefor, an extension leaf mounted on said table body so as to be movable to an extended supporting position in abutting alignment with the table top and to a contracted position under the table top, and a support for the extension leaf comprising a slide bar carrying said leaf and slidible in an aperture in said end rail, said aperture having an anti-friction bearing on its lower surfaces and a constricted neck portion open at the top of said rail, and said slide bar being slidible over said anti-friction bearing and having a constricted body portion extending from top to bottom thereof and completely passable through said constricted neck portion only when the leaf is moved to a position extended beyond its supporting position in which said constricted body portion is in alignment with said neck portion, and unconstricted part of said slide bar larger than said neck portion resting on and being supported by the top of said rail on said constricted neck when the leaf is in its supporting position in abutting alignment with the table top.

4. The table of claim 3, in which said aperture is of a keyhole shape in cross-section, said constricted neck portion of which extends to and is open at the top of said end rail and in which said slide bar is of a circular cross-section slightly less than that of the rounded part of said keyhole aperture except for a flattened portion of a width less than the width of said constricted neck portion, said flattened portion defining said constricted body portion.

5. The table of claim 3, in which said aperture is of a cross-section corresponding to a portion of a circle greater than a semi-circle but less than a full circle, the missing portion of the circle defining said constricted neck portion, and in which said slide bar comprises a metal tube of circular cross-section the diameter of which is less than the diameter of said aperture and greater than the width of said constricted neck portion, said constricted body portion of said slide bar having a width less than that of said constricted neck portion so as to be passable therethrough.

6. The table of claim 3, in which said aperture is of a keyhole shape in cross-section, said constricted neck portion of which extends to and is open at the top of said end rail, and in which said slide bar is of a circular cross-section slightly less than that of the rounded part of said keyhole aperture except for a portion of a width less than the width of said constricted neck portion, said portion defining said constricted body

portion, said slide bar carrying a stop element which in cooperation with said table body limits the extensibility of said extension leaf to the position where the constricted portion of said slide bar comes into registration with the constricted neck portion of said aperture.

7. The table of claim 3, in which the abutting surfaces of said extension leaf and said table top are provided with interlocking portions so shaped that the said table top will provide additional support for said extension leaf when the two are in abutting alignment.

8. In an extension leaf table having a table body including an end rail, a table top, and supporting legs therefor, an extension leaf mounted on said table body so as to be movable to an extended supporting position in abutting alignment with the table top, and to a contracted position under the table top, and a support for the extension leaf comprising a slide bar of generally circular cross-section carrying said leaf and slideable in an aperture in said end rail, said aperture having a constricted neck portion open at the top of said rail and said slide bar having a flattened body portion extending from top to bottom thereof and completely passable through said constricted neck portion when the leaf is moved to an extended position in which said flattened body portion is in alignment with said neck portion, an unflattened part of said slide bar larger than said neck portion resting on and being supported by the top of said rail on said constricted neck portion when the leaf is in abutting alignment with the table top.

9. In an extension leaf table having a table body including an end rail, a table top, and sup-

porting legs therefor, an extension leaf mounted on said table body so as to be movable to an extended supporting position in abutting alignment with the table top and to a contracted position under the table top, and a support for the extension leaf comprising a slide bar in the form of a hollow metal tube of circular cross-section carrying said leaf and slideable in an aperture in said end rail, said aperture being of circular cross-section and having a constricted neck portion open at the top of said rail and said slide bar having a flattened body portion extending from top to bottom thereof and completely passable through said constricted neck portion when the leaf is moved to an extended position in which said flattened body portion is in alignment with said neck portion, an unflattened part of said slide bar larger than said neck portion resting on and being supported by the top of said rail on said constricted neck portion when the leaf is in abutting alignment with the table top.
